(57) **CLAIM**

The ornamental design for a lamp for a vehicle, as shown and described.

DESCRIPTION

FIG. 1 is a top-front-left side perspective view of a lamp for a vehicle showing our new design;

FIG. 2 is a bottom-front-left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the portion 9 of FIG. 1.

The broken lines illustrate portions of the lamp for a vehicle that form no part of the claimed design. Additionally, the broken lines used in FIGS. 1 and 9 to illustrate the boundaries of the enlarged portion views form no part of the claimed design.

1 Claim, 5 Drawing Sheets
